UNITED STATES PATENT OFFICE.

FREDERICK F. HORN, OF COLORADO SPRINGS, COLORADO.

DESIGN FOR A SPOON.

SPECIFICATION forming part of Design No. 22,229, dated February 21, 1893.

Application filed December 24, 1892. Serial No. 456,281. Term of patent $3\frac{1}{2}$ years.

To all whom it may concern:

Be it known that I, FREDERICK F. HORN, a citizen of the United States, residing at Colorado Springs, in the county of El Paso, State of Colorado, have invented and produced a new and original Design for a Spoon, of which the following is a specification, reference being had to the accompanying drawing, illustrating the same.

My design resides in the peculiar shape of the shank or stem by which the handle or bowl are connected, and which, as shown in the drawing, consists of a tapering body C, which is connected at its upper end to the handle B, and at its lower end with a substantially rectangular shaped piece, C'. Said

piece C' is provided on opposite sides with laterally projecting triangular shaped arms, D, and on its lower side with a depending piece, E. The handle of the spoon, in connection with the laterally projecting triangular shaped arms, D, will be a miniature representation of the long pick commonly employed by miners.

I claim—

The design for a spoon substantially as herein shown and described. 25

FREDERICK F. HORN.
